UNITED STATES PATENT OFFICE

120,013

DESIGN FOR AN AUTOMOBILE BODY

Willard L. Morrison, Lake Forest, Ill.

Application December 24, 1936, Serial No. 66,732

Term of patent 3½ years

To all whom it may concern:

Be it known that I, Willard L. Morrison, a citizen of the United States, residing at Lake Forest, in the county of Lake and State of Illinois, have invented a new, original, and ornamental Design for an Automobile Body, of which the following is a specification, reference being had to the accompanying drawing, forming part thereof.

Fig. 1 is a side perspective view of an automobile body showing my new design.

Fig. 2 is a plan view of the automobile body trim shown in solid lines in Fig. 1, on a reduced scale.

Fig. 3 is a front view of the automobile body trim shown in solid lines in Fig. 1, on a reduced scale.

Fig. 4 is an enlarged sectional view through the trim, taken on line 4—4 of Fig. 1.

The characteristic features of the automobile body design are indicated in solid black lines in the drawing, the beaded elements being connected by webbed portions.

I claim:

The ornamental design for an automobile body, substantially as shown and described.

WILLARD L. MORRISON.
